FIRE HYDRANT

James W. Dashner, Elmira, N.Y., assignor to International Telephone and Telegraph Corporation, Nutley, N.J.

Filed Apr. 12, 1973, Ser. No. 350,556

Term of patent 14 years

Int. Cl. D23—01

U.S. Cl. D23—12

Fig. 1

Fig. 2

Fig. 3

Fig. 4

FIG. 1 is a front perspective view of a fire hydrant embodying the new design;

FIG. 2 is a side elevational view thereof;

FIG. 3 is a rear elevational view thereof; and

FIG. 4 is a top plan view thereof.

The broken line representation of retention cables in FIG. 1 is for purposes of illustration only.

I claim:

The ornamental design for a fire hydrant, substantially as shown and described.
